(57) **CLAIM**

The ornamental design for a container for packaging, as
shown and described.

DESCRIPTION

FIG. 1 is a right side elevational view of container for pack-
aging, in open position.

FIG. 2 is a front elevational view thereof, in open position.

FIG. 3 is a top plan view thereof in open position.

FIG. 4 is a bottom plan view thereof in open position.

FIG. 5 is a front elevational view thereof in closed position.

FIG. 6 is a top plan view thereof in closed position.

FIG. 7 is a vertical sectional view thereof taken along a line
7—7 of FIG. 3, in open position.

FIG. 8 is a vertical sectional view thereof taken along a line
8—8 of FIG. 1, without the lid; and,

FIG. 9 is a vertical sectional view thereof taken along 9—9 of
FIG. 6 in closed position.
